UNITED STATES PATENT OFFICE

HENRY CREAMER, OF NEW YORK, N. Y.

STEAM FEED-WATER TRAP.

SPECIFICATION forming part of Letters Patent No. 313,854, dated March 17, 1885.

Application filed March 28, 1884. (No model.)

To all whom it may concern:

Be it known that I, HENRY CREAMER, a citizen of the United States, and a resident of New York, in the county of New York and 5 State of New York, have invented certain new and useful Improvements in Steam Feed-Water Traps, of which the following is a specification.

The object of my invention is to produce an 10 automatic steam feed-water trap which will operate in any position below or above the boiler, can be used with cold or hot water, and work successfully under varying pressures.

It consists of a double cylindrical vessel provided with separate chambers of different diameters for holding the water and steam. Into 15 these chambers, working simultaneously, is placed a double piston.

In order to more fully describe my invention, I refer to the accompanying drawings.

Figure 1 is a sectional elevation on line *x x*, Fig. 2. Fig. 2 is a plan section on line *y y*, Fig. 1. Fig. 3 is detached side view of the 20 valve-gear, showing the relative position of one valve with the other.

A represents a hollow steam cylinder or vessel, to which is attached the water-cylinder *B*, closed at one end. Into this steam-cylinder *A* is fitted the piston *C*, and into the water-cylinder *B* is fitted the piston *D*. These 25 two pistons are joined together by hollow tube *E*. These pistons are fitted to their respective parts in the usual manner.

To the piston *C* is fastened the exhaust-valve *a*, which is opened when the said piston reaches 30 the end of the stroke by the stem *e* coming in contact with the upper ledge, *f*, of the water-cylinder *B*, and when the said valve is opened it is held in position by the spring *g*.

40 Into the tube or rod *E* is inserted the stem *h* of the valve *I*. To this stem, at *j*, is fastened the float *k*. The valve *I* is seated on the bottom of the piston *D*.

In the rod *E*, above the piston *D*, are openings *f'*, (shown in dotted lines, Fig. 1,) and the object of these holes *f'* is for permitting the water to pass through the piston *D* into the chamber *B*. The stem *h* is reduced in size, so as to not obstruct the openings *f'*. When 45 the valve is open, it is retained in position by pin *m*, fastened to stem *h*, and which moves freely up and down in the slot *n* in one side of

the rod *E*. The pistons *C* *D* and the rod *E* are counterbalanced by the lever-arm *O* and weight *P*, attached thereto, outside of the said cylinders. This lever-arm *O* is fulerumed at *o*, and this fulerum-support consists of a hollow shaft, *p*, to which the arm *O* is attached, and passing through a stuffing-box, *o'*, into the chamber *A*, and is secured to a short arm, 55 *o''*. This short arm is provided with a roller, *o'''*, resting against the projecting arm *e'* on the rod *E*.

On one side of the rod *E* is fastened the rib or feather *e''*, which moves freely up and down 60 in the notch *e'* in the plate *b'*, which is fastened to the lower base of cylinder *A*. The object of this is to prevent the pistons from turning around.

Through the hollow shaft *p* the valve-shaft 70 *q* passes, to the end of which is secured the arm *r*, resting on the pin *m* of the valve *I*, and on the other end, beyond the lever *O*, is attached the arm *g'*, (see Fig. 3,) on which there is a counter-weight, *g''*. To this arm *g'* is attached the arm *g''*, which is connected to the steam-valve *T* and water-valve *U* by rod *v* and *w*.

The operation is as follows: Water from the main pipes or condensation from the radiating 80 pipes flows through the valve *U* into the lower part of the chamber *A* through the opening *f'* in hollow rod *E*, filling the chamber *B* until it reaches the float *k*, when the said float *k* rises and rotates the arm *r* sufficient to allow weight 85 *g''* on arm *g'* to pass the center, when it will fall by its own gravity, and thereby cause the water-valve *U* to be closed and the steam-valve *T* to be opened, and the steam will thus be communicated to the chamber *A* above the 90 steam-piston, forcing the two pistons downward, and expelling the water from the chamber *B* into the boiler through the pipe *w'*. As the pistons descend they raise the counter-weight *P* by aid of arms *O* *o''*, rotating on the 95 fulerum at *o*. In this case the steam-valve *T* remains open until the projection *e''* on the under side of the steam-piston *C* engages the arm *r* and carries it back to its position, as shown in full line, Fig. 1, when the steam-valve *T* is closed and the water-valve *U* opened. At the same instant that the steam is shut off 100 the exhaust-valve *a* is opened by the stem *e* coming in contact with the ledge *f* of cylinder

der B, allowing the steam to escape below the pistons C D into the chambers A B. This valve is held open by the spring g until the counter-weight O brings the piston to the top 5 of the cylinder. In this case the top of the valve a comes in contact with the cylinder-head a^2 , and closes the same ready for the next operation.

What I claim is—

- 10 1. In a steam feed-water trap, the combination of the pistons C and D, joined together by hollow tube E, which is provided with openings f' , with the water-cylinder B, the steam-cylinder A, joined as shown, and the valve a, substantially as and for the purpose set forth.
- 20 2. In a steam feed-water trap, the combination of the pistons C and D, joined together by hollow tube E, with the lever O, weight P, hollow shaft p, short arm o^2 , roller o^3 , arm e, and cylinders A and B, substantially as and for the purpose set forth.

3. In a steam feed-water trap, the combination of the float k with arm r, weight g, stem h, tube E, valves U and T, and cylinders A 25 and B, substantially as and for the purpose set forth.

4. In a steam feed-water trap constructed as described, the exhaust-valve a, with stem e, in combination with the piston C, spring e', ledge f, and cylinder B, substantially as and 30 for the purpose set forth.

5. In a steam feed-water trap, the cylinders A B, pistons C D, valve a, float k, valve I, arms $r o^2 g^4$, with weight g^5 , lever-arm O, with 35 weight p, arms $v w$, and valves T U, all arranged substantially as and for the purpose set forth.

Signed at New York, in the county of New York and State of New York, this 22d day of March, A. D. 1884.

HENRY CREAMER.
